UNITED STATES PATENT OFFICE.

JOSEPH VALCAUDA, OF SEATTLE, WASHINGTON.

DIRECTION-INDICATOR.

1,297,612.

Specification of Letters Patent. Patented Mar. 18, 1919.

Application filed May 9, 1918. Serial No. 233,597.

To all whom it may concern:

Be it known that I, JOSEPH VALCAUDA, a citizen of the United States, residing at Seattle, in the county of King and State of Washington, have invented certain new and useful Improvements in Direction-Indicators, of which the following is a specification.

This invention has relation to direction indicators, and the nature and objects thereof will be readily apparent to those skilled in the art to which this invention appertains in the light of the following explanation of the accompanying drawings, illustrating what I now believe to be the preferred embodiment or mechanical expression, of my invention, from among other forms and arrangements thereof, within the spirit of the invention, or the scope of the appended claims.

An object of the invention is to provide a direction indicator embodying a uni-directional indicator to point constantly toward a single point of the compass, and means for rendering audible any deviation of the pointer from a predetermined location relative to its support.

Another object of the invention is to provide a direction indicator particularly designed to render assistance to blind persons to enable them to continue on a predetermined course.

Another object of the invention is to provide a direction indicator for blind persons embodying a magnetic compass needle, a pair of audible signals one to be located at each side of the person, and certain contacts and connections correlating the various elements of the apparatus so that a deviation of the person from a predetermined course may be manifested by an energization of the one or the other of the signals as the case may be, thereby directing the person toward a proper course.

A still further object of the invention is to provide a direction indicator having the characteristics above set forth including a casing embodying a magnetic needle, with a pair of contact points adjustable toward and away from the needle and adapted to be disposed at opposite sides thereof with a pair of audible signals, and a circuit and source of current correlating the elements

of the apparatus whereby a deviation of the needle from a point mid-way between the contacts, in either one direction or the other will cause the needle to engage one of the contacts and thereby cause the energization of the corresponding signal connected thereto for the purpose above set forth.

In addition to the foregoing my invention comprehends improvements in the details of construction and arrangement of the correlative parts to be hereinafter more fully described and particularly set forth in the appended claims.

In the accompanying drawings in which similar and corresponding parts are designated by the same characters of reference throughout the several views in which they appear:

Figure 1, is a view in side elevation of a direction indicator showing diagrammatically the signals and the manner in which they are connected with the indicator.

Fig. 2, is a view of the indicator in plan.

Fig. 3, is a horizontal section taken through the indicator and

Fig. 4, is a view of the indicator in transverse section.

With reference to the drawings, 10 indicates a cylindrical casing which is mounted upon a base plate 11 of insulating material. The upper edge or rim 12 of the casing is bent to form an outer groove 13 surrounding the rim of the casing for a purpose which will be presently noted.

The bottom plate of the casing is formed with a central circular opening 14, and a circular plate 15 is secured to the base plate 11 and located within said opening 14 concentrically thereto. Mounted centrally upon the plate 15 is a pin 16 forming a support for a magnetic needle 17 whereby the needle may freely rotate to constantly point toward one cardinal point of the compass. The casing is closed by means of a circular cover 18 having its periphery formed with a flange 19 shaped to seat in the groove 13 whereby the cover may be snapped in place upon the casing and when in place permitted to freely rotate. The periphery of the flange 19 is serrated as at 20, and a leaf spring 21 is secured at one end to the exterior of the casing and is permitted to engage at its free end the serrated portion 20 of its cover so

as to retain said cover in any adjusted or rotated position relative to the casing. The cover 18 is formed adjacent its periphery with an arcuate slot 22. Extending through 5 the slot 22 are a pair of screws 23 having enlarged and kerfed heads 24 whereby they may be readily rotated by means of a screw driver. Each screw 23 loosely passes through an apertured disk 25, each disk being 10 formed with an extension 26 to hold the wire under the screw head when it is attached thereto. Each screw 23 furthermore extends through a disk of insulating material 27, said disk being located upon the top 15 of the cover and of such diameter as to exceed the width of the slot 22. Each screw is furthermore passed through a disk 28 having a central reduced portion of a diameter corresponding to the width of the slot 22 20 so as to extend thereinto, the enlarged portion of the disk 28 bearing against the under side of the cover as clearly shown in Fig. 4. Each screw 23 is furthermore provided with a reduced extension 29 forming 25 a contact. The screws 23 are disposed at opposite sides of the needle 17 as shown in Fig. 2 so as to be engaged by the needle when the needle is deflected from its normal position midway therebetween. It will 30 be obvious that either screw 23 may be moved along the slot from one end to the other by rotation of the screw sufficiently to loosen the disks 27 and 28, rotation of the screw to drive the same home, effecting a 35 binding of the disk 28 against the cover so as to secure the screw in place subsequent to adjustment.

To correlate the elements of my invention I provide a pair of audible signals such as 40 buzzers, electric bells or the like, indicated at 30 and 31 in Fig. 1. One terminal of the signal 30 is connected by means of a lead 32 to one screw 23, the left hand one being indicated in Fig. 1, while one of the terminals of the other signal member 31 is connected by means of a lead 33 to the other (right hand) screw 23. The other terminals of the signals 30 and 31 are then connected together and to one pole of a battery 34 by 45 means of conductors 35, while the other pole of the battery is connected by means of a lead 36 to the central plate 15 within the casing mentioned above.

In use, the casing 10 is secured to the person by any suitable means. I have illustrated in Fig. 1 of the drawings a hook 37 secured to the casing at one side and adapted to enter a socket 38 formed upon a plate 39 which may be part of a belt, or which may 55 be a plate secured to the belt. The signals 30 and 31 are located at each side of the person so that when the signals are sounded, the person may readily distinguish which signal has been sounded by their proximity 60 to one ear or the other. The cover 18 is

rotated so as to dispose the contacts 29 at equi-distant points from the needle 17 when said needle has come to rest. This adjustment is effected after the person has faced the proposed direction of travel. The person may now continue to walk in the proper direction and any deviation from a practically straight line connecting the point of departure with the point of destination will be manifested to his senses by energization 70 of either one signal or the other. For instance, should the person turn slightly toward the right, the left hand contact 29 will be brought into engagement with the needle and as a result current will pass from 80 the battery 34 along one of the conductors 35 and into the signal 30 leaving said signal and traversing the conductor 32. The current enters the left hand end contact 29, thence passing through the needle 17 into the 85 disk 15, and returning through the conductor 36 to the battery. The left hand signal will then be energized and will continue to sound until the person has again turned toward the left, and proceeds along the predetermined 90 course. Conversely, a movement of the person toward the left of the proposed course will be manifested by energization of the other signal, the circuit being traced in an obvious manner. When the course is to be 95 changed the cover is again rotated so as to dispose the contacts 29 at points equi-distant from the needle when the same is at a position of rest.

The foregoing description and the drawings have reference to what may be considered the preferred, or approved form of my invention. It is to be understood that I may make such changes in construction and arrangement and combination of parts, materials, dimensions, etc., as may prove expedient and fall within the scope of the appended claims.

Having thus described my invention what I claim as new and desire to secure by Letters Patent is:—

1. A direction indicator comprising a cylindrical casing, a magnetic needle mounted therein, a cover mounted for rotary adjustment upon the casing and having a slot struck on an arc around its center, a pair of contacts adjustably mounted within said slot and adapted to be placed at opposite sides of the normal position of the needle, a source of electricity, two signals, leads connecting them respectively with said contacts, and a wire leading from the signals through said source of electricity to said needle.

2. In a direction indicator, the combination with a cylindrical casing, a cover rotatably mounted thereon and having a serrated periphery and an arcuate slot in its body, and a leaf spring on the casing engaging said periphery; of a magnetic needle

mounted within said casing, a pair of contacts adjustably mounted in the ends of said slot and insulated from the cover, a source of electricity, a pair of signals, wires leading from the contacts to the signals, and a wire leading from the signals through said source of electricity to said needle.

In testimony whereof I affix my signature in presence of two witnesses.

JOSEPH VALCAUDA.
